METHOD OF AND APPARATUS FOR SPINNING COTTON AND OTHER TEXTILE FIBERS

Marion S. Mayo, Los Angeles, Calif.

Application July 23, 1945, Serial No. 606,622

11 Claims. (Cl. 57—34)

1

This invention relates to the spinning of fibers, and more particularly to a novel method of and apparatus for spinning cotton and other textile yarns.

The general object of the invention is to provide a new and improved method of and apparatus for spinning cotton and other textile yarns, whereby the fibers are more thoroughly separated, paralleled and spun into an appropriately twisted yarn for delivery to a mechanical twister and spooler.

A more particular object is to provide a method and apparatus of the character stated whereby cotton and other textile fibers are pneumatically separated, paralleled and spun into an appropriately twisted yarn for delivery to a mechanical twister and spooler.

A further object is to provide a method and apparatus of the character stated whereby a cleaner yarn is produced.

Other objects and advantages will appear as this specification progresses.

The invention is illustrated in the annexed drawing which forms a part of this specification, and in which:

Fig. 1 is a schematic view of my invention.

Fig. 2 is a horizontal section of the cyclone chamber taken on line 2—2 of Fig. 1.

In the drawing, in which the same parts are designated by the same reference numerals in both figures, is illustrated an apparatus for practicing my method, which apparatus includes generally a bale opener 1, a storage cell 2, a separating and adjusting chamber 3, and a cyclone chamber 4. Below the lower end of said cyclone chamber 4 is illustrated a mechanical twister 5 and a spooler 6.

The bale opener 1 comprises an air chamber 7, a bale supporting platform 8 mounted in said chamber on the upper end of an hydraulic plunger 9, an air-jet nozzle 10 in the upper part of said chamber 7, and an outlet funnel 11 mounted in the upper part of said chamber opposite the end of said jet nozzle 10. The air chamber 7 may include a hinged cover 12 for its upper end, which end of the chamber is formed with an external flange 13 upon which said cover rests in its closed position, said cover being hinged at one edge to said flange by a hinge 14, and clamped at its opposite edge to said flange 13, in its closed position, by a clamp 15. The hydraulic plunger 9 extends downwardly from the platform 8 through a bearing 16 in the lower end of the chamber 7 into an hydraulic cylinder 17. The jet nozzle 10 is connected to the remote end of a pipe 18 leading from a high pressure air compressor (not shown) into the upper part of the chamber 7.

The storage cell 2 may be a receptacle of inverted frusto-conical form, constructed with an

upper end wall 19, but without a lower end wall, and said chamber includes an equalizing valve 20 in the upper end of the cell for opening under a predetermined degree of air pressure and allowing air to escape from the cell, whereby the pressure of the air in the cell is prevented from rising above said predetermined degree.

From the smaller end of the funnel 11 extends a duct 21 outwardly through the upper part of the bale-opener chamber 7 and through the upper end wall 19 of the storage cell 2 into the upper end of said cell.

The separating and adjusting chamber 3 may be a receptacle of cylindrical form tapered from its lower portion to its lower end to a small diameter. The upper end of said chamber is open, but is closed part of the time by a weighted trap door 22, while the lower end of said chamber is constructed with a weighted valve 23 for closing said end part of the time. The separating and adjusting chamber 3 is located with its upper end directly under the lower end of the storage cell 2. A plurality of air-jet nozzles 24 are extended through the cylindrical wall of the carding chamber 3 at one side of said chamber, and a plurality of nozzles 25 are extended through the cylindrical wall of said chamber at the opposite side of said chamber, which nozzles are respectively spaced longitudinally of the separating and adjusting chamber 3 and are connected, respectively, to pipes 26 and 27, which pipes are connected to a pipe 28 leading from a high pressure air compressor (not shown).

The cyclone chamber 4 may be of double conical formation, with its largest diameter, indicated at 29, nearer its upper end than its lower end, and tapering upwardly and downwardly, respectively, from said largest diameter to a smaller diameter at its upper end 30, corresponding to the diameter of the lower end of the separating and adjusting chamber 3, and to a very small diameter at its lower end 31 of sufficient dimensions only to permit a yarn appropriately twisted to pass therethrough and be delivered from said cyclone chamber. Air-jet nozzles 32 and 33 extend substantially tangentially to and slightly downwardly into the cyclone chamber 4 through its conical wall below its largest diameter 29, which nozzles are connected to a pipe 34 leading from a high-pressure air compressor (not shown). The air-jet nozzles 32 and 33 are at such position to the cyclone chamber 4 that jets of air under high pressure delivered therefrom will give a "cyclonic" or swirling motion to the air and the fibers in said cyclone chamber. The cyclone chamber 4 is located with its upper open end 30 directly below the lower reduced end of the separating and adjusting chamber 3.

By means of my apparatus as above described

I practice my method of spinning fibers into yarn, as follows:

The cover 12 of the chamber 7 of the bale opener 1 being unclamped and swung open on its hinge 14, a bale of cotton 35 is placed upon the raised platform 8, and said platform and bale are lowered in said chamber by the hydraulic cylinder 17 and plunger 9, until the upper side of said bale is below the top of said chamber, whereupon the cover 12 is swung closed over the top of said chamber and clamped in such position by the clamp 15. A jet of air under high pressure is delivered from the nozzle 18 against the upper side of the bale of cotton 35, whereupon the upper cotton fibers are removed from said bale and delivered by said air jet into the funnel 11 and forced through said funnel and the duct 21 into the storage cell 2, opening the weighted trap door 22, from which storage cell said fibers are forced by the jetted air pressure into and through the separating and adjusting chamber 3, opening the weighted valve 23, from which separating and adjusting chamber the carded fibers are forced by the air pressure into and through the cyclone chamber 4, the fibers being separated and adjusted in the separating and adjusting chamber 3 while passing therethrough, by the jets of air under high pressure from the jets 32 and 33, whereby the fibers are paralleled, and are appropriately twisted into yarn at the lower restricted end of the cyclone chamber, from which end of said chamber the yarn is delivered to the mechanical twister 5, which stabilizes the twist of the yarn and delivers said twisted yarn to the spooler 6, which winds said yarn onto spools, tubes or cones in the conventional manner.

I claim:

1. Apparatus including a cyclone chamber into which cotton or other fibers may be introduced, said chamber being formed with a reduced open end, and air nozzles extending tangentially into and toward said reduced end of said chamber for directing jets of air under high pressure into said chamber for subjecting the cotton and other fibers to a swirling and conical spiral motion for paralleling and spinning said fibers into yarn.

2. Apparatus including a chamber, means for introducing cotton or other fibers into said chamber and means for pneumatically subjecting the fibers in said chamber to a swirling and conical spiral motion for paralleling and spinning said fibers into yarn.

3. Apparatus including a chamber, means for introducing cotton or other fibers into said chamber, and means for pneumatically separating and adjusting said fibers in said chamber.

4. Apparatus including a chamber into which cotton or other fibers may be introduced, and nozzles extending into said chamber for directing jets of air under high pressure into said chamber for separating and adjusting the fibers in said chamber.

5. Apparatus including a chamber provided with an outlet, means in said chamber upon which a bale of cotton or other fibers may be operatively supported for removal of fibers therefrom, and means for pneumatically removing the fibers from said bale in said chamber and forcing the said removed fibers out of said chamber through said outlet.

6. Apparatus including a chamber provided

with an outlet in which a bale of cotton or other fibers, may be placed, and a nozzle through which air under high pressure may be jetted upon said bale for removing the fibers from the bale and forcing said removed fibers out of said chamber through said outlet.

7. Apparatus including a chamber provided with an outlet, an elevator platform on which a bale of cotton or other fibers may be placed, a nozzle through which air under pressure may be jetted upon said bale for removing the fibers from said bale and forcing said removed fibers out of said chamber through said outlet, and means for operating said elevator platform to maintain said bale in position to be acted upon by the jet of air from said nozzle.

8. Apparatus including a bale opener for pneumatically removing fibers from a bale, a pneumatic fiber separating and adjusting means connected to said bale opener for receiving the removed fibers from said bale opener and separating and adjusting said fibers, and means connected to said carder for receiving the carded fibers from said carder for pneumatically paralleling and spinning said separated and adjusted fibers into yarn.

9. The method comprising pneumatically removing fibers from a bale, pneumatically separating and adjusting said removed fibers, and pneumatically paralleling and spinning said separated and adjusted fibers into yarn.

10. Apparatus as characterized by claim 1 including a conventional twister for receiving the yarn, as it is delivered from the reduced open end of the cyclone chamber, for stabilizing the twist of said yarn.

11. Apparatus including a bale opener for pneumatically removing fibers from a bale, a storage cell connected at one end to said bale opener, into which cell said removed fibers are pneumatically forced by said bale opener, a pneumatic separating and adjusting means connected at one end to the other end of said storage cell for receiving said fibers from said cell, a weighted trap door between said other end of said storage cell and said end of said separating and adjusting means, a cyclone chamber connected at one end to the other end of said separating and adjusting means, into which cyclone chamber said fibers are received from said separating and adjusting means, a weighted valve between the connected ends of said separating and adjusting means and said cyclone chamber, the other end of said cyclone chamber being reduced and open, means for pneumatically paralleling and spinning the fibers in said cyclone chamber into yarn and delivering said yarn from said chamber through its reduced open end, and a conventional twister for receiving said delivered yarn and imparting further twist thereto.
